(57) **CLAIM**

The ornamental design for a display screen with a graphical user interface for a scale, as shown and described.

DESCRIPTION

FIG. 1 is a front view of a first embodiment of display screen with a graphical user interface for a scale; and, FIG. 2 is a front view of a second embodiment of display screen with a graphical user interface for a scale. The broken line showing of the display screen, text, and graphic features forms no part of the claimed design.
